COMBINATION PAINT STIRRER AND
BRUSH HOLDER

George L. Hoffman, Miami, Fla.

Application July 9, 1946, Serial No. 682,329

3 Claims. (Cl. 248—110)

1

The invention relates to a device for effectively stirring and mixing liquid paint in a can, and more particularly to a paint stirring device which is adapted to be supported in a paint can in such manner as to hold a paint brush over the can.

Common practice in using a can of freshly opened paint is to first stir the paint with a wooden paddle, after which a paint brush is dipped into the liquid paint for applying the same. In using a wooden paddle or the like, the body of the paint which has settled to the bottom of the can is "lumped" or coagulated by the lower end of the paddle, which prolongs the time required to thoroughly mix the paint into a uniform consistency. Moreover, when the paint is being used by dipping a brush into the same, it is frequently desirable to put the brush down from time to time, and it is common practice to lay the brush across the top of the can where it is easily knocked off and where the ends of the brush bristles overhang the edges of the can and allow paint to drip down the outside thereof.

It is an object of the present invention to provide a novel paint stirrer and brush holder which will mix the paint to a uniform consistency and at the same time provide means for holding a paint brush in position over a can of paint having the stirrer inserted therein.

Another object is to provide a novel paint stirrer which will mix paint to a uniform consistency without lumping the paint.

A further object is to provide a novel paint stirrer made of wire and having an offset rim engaging portion cooperating with the stirrer to support the handle of a paint brush.

A still further object is to provide a novel paint stirrer and brush holder which may be inexpensively constructed of a single piece of wire, and which accomplishes all of the foregoing objectives.

These and other objects are accomplished by the parts, arrangements and combinations which comprise the present invention, the nature of which is set forth in the following general statement, and a preferred embodiment of which is set forth in the following description and illustrated in the accompanying drawing and which is particularly and distinctly pointed out and set forth in the appended claims forming part hereof.

In general terms, the novel paint stirrer and brush holder comprising the invention may be stated as including a wire stirrer having a bottom loop for stirring paint in a can and a top handle loop, the lower end of the bottom loop having a sharpened edge for scraping the can

2

bottom, and a brush holder loop offset from and connected to the stirrer between its top and bottom loops, said offset loop being adapted to engage over the brim of a can and to cooperate with the handle loop for holding a paint brush in position over the can.

Referring to the drawing forming part hereof, in which a preferred embodiment of the invention is shown by way of example;

10 Figure 1 is a plan view of the improved combination paint stirrer and brush holder;

Fig. 2 is a side elevation thereof;

Fig. 3 is a perspective view on a reduced scale of the improved stirrer in use in stirring paint in 15 a can; and

Fig. 4 is a similar view showing the improved stirrer in position holding a paint brush over the can of paint.

Similar numerals refer to similar parts 20 throughout the several views of the drawing.

As shown in the drawing, the novel paint stirrer and brush holder may be conveniently and inexpensively made from a single piece of wire having one end forming the offset loop 5, and the other end 6 being twisted on the longitudinal part of the stirrer portion.

The stirrer preferably is of an elongated butterfly shape and includes an upper handle loop 7 and a lower paint stirring loop 8, both of which 30 may be substantially triangular in form as shown with the wire parts forming the loops twisted together to form a relatively stiff connection between the loops as indicated at 9.

The upper handle loop 7 may be varied considerably in shape without departing from the scope of the invention, and the shape of the lower loop 8 may also be varied to some extent, although its laterally extending bottom portion should be straight and sharpened as indicated at 40 10, in order to effectively scrape the bottom of a paint can when mixing the paint contained therein.

One leg of the upper loop 7 is a continuation of one leg of the lower loop 8 and the other leg 45 7' at its lower end forms part of the twisted connection 9 and terminates at 6. The portion 8' of the lower loop, which terminates in the end 5' of the offset loop, forms the other part of the twisted connection 9, and extends laterally therefrom at 11 from which it is bent upwardly to form the upper portion 12 of the offset loop and then is bent downwardly to form the lower portion 13 which terminates in the end 5'. As shown, between the upper and lower portions 12 and 50 13, the offset loop is preferably brought to-

gether so as to engage the end 5', to which it may be secured as by soldering for the purpose of stiffening the offset loop.

The upper and lower portions 12 and 13 of the offset loop thus form a double loop which is substantially of butterfly shape. It will be appreciated that slight variations in the shape and conformation of the offset loop, as well as the manner of connecting it to the paint stirrer member, may be made within the scope of the invention.

In forming the combination paint stirrer and brush holder out of a single piece of wire, beginning with the end 5' the wire is formed into the butterfly loop 5 which is connected to the stirrer by the offset portion 11, and the wire is then twisted around the longitudinal part 8 as indicated at 9 and then extends downwardly to form the leg 8' of the bottom triangular loop. From the leg 8', the wire extends into the flattened lateral scraper 10 and thence upwardly at right angles through the twisted portion 9 to become the one leg of the upper loop 7. From the leg 7' of loop 7 the wire extends downwardly into twisted portion 9 and terminates in the end 6.

As indicated in Fig. 3 when the improved stirrer is held at the handle loop 7 and rotated in a can of paint, the bottom loop 8 functions to thoroughly mix the paint, and the scraper portion 10 frees the paint which has settled to the bottom of the can without lumping the same and thoroughly and uniformly mixes it into the rest of the liquid. Due to the fact that the paint is stirred by the wire loop 8, it is more thoroughly and rapidly mixed than when stirred by a flat paddle, because each leg of the wire loop 8 and 8' and its bottom bar 10 each create a separate flow, or stream, through the paint vehicle mixing in its color, leads, zincs, or materials used in the paint. When the stirrer is lifted from the paint, it drains more rapidly because of the small area of the wire comprising the loop, and should the paint dry on the stirrer it may be easily cleaned with a putty knife, or any hard or sharp object, and used in paint of another color without bringing in undesired colors. Should it be necessary to immediately shift from one color of paint to another, the same mixer may be used by wiping clean without the use of thinner, etc.

After the paint has been thoroughly stirred and mixed, the stirrer is tilted to one side of the can and the lower portion 13 of the offset butterfly loop is positioned so as to engage over the top rim of the can. With the stirrer in this position, the paint may be used by dipping a brush such as indicated at 15 into the can and applying the paint to a desired surface. At anytime it is desired to lay the brush aside without wasting the paint or allowing the brush bristles to drip, the handle 16 of the brush is inserted through the handle loop 7 and the upper portion 12 of the offset loop, in which position the brush handle is held as indicated in Fig. 4 with the bristles over the can, the bottom part of the handle being wedged in the bottom of the handle loop 7 and the upper portion of the handle engaging the lateral part 17 of the offset loop.

The novel paint stirrer is simple and inexpensively made of a single piece of wire and provides for rapidly mixing paint in a can to a uniform

consistency without lumping, while at the same time providing means for holding a paint brush over the can with the stirrer inserted therein.

In the foregoing description, certain terms have been used for brevity, clearness and understanding, but no unnecessary limitations are to be implied therefrom beyond the requirements of the prior art, because such words are used for descriptive purposes herein and are intended to be broadly construed.

Moreover, the embodiment of the improved construction illustrated and described herein is by way of example, and the scope of the present invention is not limited to the exact details of construction.

Having now described the invention, the construction, the operation and use of a preferred embodiment thereof, and the advantageous new and useful results obtained thereby; the new and useful constructions, and reasonable mechanical equivalents thereof obvious to those skilled in the art, are set forth in the appended claims.

I claim:

1. A combination paint stirrer and brush holder including a wire stirrer member having a top handle loop and a substantially triangular bottom loop with a straight sharp edge at its base, said top and bottom loops having a twisted wire connection with each other, a brush holder loop laterally offset from and attached to said connection, and said brush holder loop having a lower portion adapted to engage over the brim of a can of paint and an upper portion for cooperating with said top handle loop to hold a paint brush in position over said can.

2. A combination paint stirrer and brush holder including a wire stirrer member of elongated butterfly shape having a top handle loop and a bottom stirrer loop with a twisted wire connection between the loops, and a brush holder member attached to and laterally offset from said connection, said brush holder member being of substantial butterfly shape and having a lower loop for engaging over the brim of a can of paint and an upper loop for cooperating with the top handle loop of said stirrer member to hold a paint brush in position over said can.

3. A combination paint stirrer and brush holder made of a single piece of wire and including a top handle loop and a bottom stirrer loop with a twisted wire connection between the loops, the lower end of said bottom loop having a laterally extending straight sharp edge, and a brush holder member laterally spaced from said connection, said brush holder member having a lower loop for engaging over the brim of a can of paint and an upper loop for cooperating with said top handle loop to hold a paint brush in position over the can.

60. GEORGE L. HOFFMAN.
